UNITED STATES PATENT OFFICE.

ROBERT YOUNG, OF TACOMA, WASHINGTON.

HOT-BLAST STOVE.

SPECIFICATION forming part of Letters Patent No. 715,188, dated December 2, 1902.

Application filed March 26, 1902. Serial No. 100,120. (No model.)

To all whom it may concern:

Be it known that I, ROBERT YOUNG, a citizen of the United States, residing at Tacoma, in the county of Pierce and State of Washington, have invented new and useful Improvements in Hot-Blast Stoves, of which the following is a specification.

My invention relates to regenerative hot-blast stoves, the object of the same being to provide means whereby hydrogen gas may be generated therein to mix with the heated air, and thereby produce a hydro-oxygen hot blast for delivery into a furnace.

The invention consists in the provision of a mass of refractory metallic substance in the stove and means for introducing high-pressure steam into the stove into contact with said metallic substance, whereby the steam is decomposed by the refractory metallic substance setting free hydrogen gas, which mixes with the heated air passing through the stove.

The invention also consists in certain features and details of construction, which will be hereinafter more fully described and claimed.

In order that my invention may be more fully understood, I have illustrated in the accompanying drawings one embodiment thereof, of which I will now proceed to describe in detail.

In said drawings, Figure 1 is an elevation, partly in section, of a hot-blast stove embodying my improvements; and Fig. 2 is a horizontal section taken partly through the brick checker-work and partly through the mass of refractory metallic substance above the same.

Like reference-numerals refer to like parts in the different views.

The casing 1 of the stove, which has been shown as cylindrical in form, but which may be of any other suitable shape, has a vertical partition 2 therein extending from the bottom to a short distance from the top, forming the vertical uptake-flue or combustion-chamber 3 and the regenerative chamber 4. Leading into the combustion-chamber 3, at a point near the lower end thereof, is a valved gas-inlet pipe 5, and also leading into said combustion-chamber at one or more points are the valved air-inlets 6. Leading from

the combustion-chamber 3, preferably at a point near its lower end, is the valved discharge pipe or flue 7, which communicates with the furnace and is designed for the escape of the hydro-oxygen hot blast. Located within the regenerative chamber 4 and extending from the bottom thereof to a point adjacent to the upper end of the partition 2 is a mass of brick checker-work 8, which it is common to employ in this class of devices. Above the brick checker-work 8 is located a mass 9 of metallic refractory material. The refractory metallic material which I prefer to use and which I have found most satisfactory in use is pig-iron; but it is obvious that other metallic substances of a similar nature may be substituted therefor. Leading from the lower end of the regenerative chamber 4 is a valved chimney-flue 10, and communicating with the lower end of said regenerative chamber are one or more valved cold-blast air-inlet passages 11. Leading into the regenerative chamber 4, at a point a short distance below the mass 9 of refractory metallic material, is a steam-pipe 12, the same being itself perforated for the discharge of steam and being provided with perforated lateral branches 13 and 14. The steam-pipe 12 extends vertically along the outside of the casing 1, is provided with a controlling-valve 15, and communicates with a main horizontal steam-supply pipe 16. The said pipe 16 extends along the sides of a series of hot-blast stoves similar to that illustrated herein, the same being designed for supplying each of said stoves with steam.

To heat the stove, and particularly to heat the mass 9 of refractory metallic material and the brick checker-work 8 in the regenerative chamber 4, the valve 15 and the valves of the cold-blast inlet 11 and of the hot-blast exit-flue 7 are closed and the valves of the gas-inlet pipe 5, the air-inlet 6, and the chimney-flue 10 are opened. The gas entering through the inlet 5 is ignited within the chamber 3, and air to support combustion is admitted through the air-inlets 6. This gas burning in the combustion-chamber 3 passes upwardly around the bridge-wall formed by the upper edge of the partition 2 and thence downwardly through the regenerative chamber 4 and off to the atmosphere through the chimney-flue

10. The products of combustion raise the refractory metallic substance 9 and the brick checker-work 8 in the regenerative chamber 4 to a high degree of heat. When these parts 5 are sufficiently heated, the valves in the gas-inlet 5, in the air-inlets 6, and in the chimney-flue 10 are closed and the cold-blast valve 11 and the hot-blast discharge-flue 7 opened. The steam-valve 15 is also opened; but it is 10 preferable to allow the cold-air blast entering through the air-inlet 11 to pass through the stove for a short period of time before the steam-valve 15 is opened in order that any unconsumed gases may be carried off through 15 the discharge-flue 7 and the danger of explosion obviated. When the valve 15 is open, high-pressure steam is caused to pass through the pipe 12 and the branches 13 and 14 thereof into the regenerative chamber 4 beneath 20 the mass 9 of refractory metallic material. As the same rises it is brought in contact with the metallic substance 9 and is decomposed thereby. When pig-iron is used as the refractory metallic substance, oxid of iron is 25 formed and hydrogen is set free. This hydrogen mixing with the hot air passes down through the combustion-chamber 3 and off to the furnace through the discharge-flue 7 in the form of a hydro-oxygen hot blast.

30 I have shown and described the steam-pipe 12 as entering the regenerative chamber 4 and discharging at a point just below the mass 9 of refractory metallic material. I prefer this disposition of parts; but it is obvious 35 that said steam-pipe may enter the regenerative chamber 4 at any other suitable point. I have also shown the mass 9 of refractory metallic material as located at the upper end of the brick checker-work 8 in the regen- 40 erative chamber 4, this location being preferred on account of the fact that it is the hottest in the stove and is farthest removed from the cold-blast inlet 11. The metallic refractory substance 9 therefore is raised to the 45 highest possible degree of heat by the combustion of the gas in the combustion-chamber 3, and on account of its location the blast of air from the air-inlet 11 has an opportunity to become heated before reaching the 50 same. The said mass of refractory metallic substance therefore will be heated to a greater extent and will retain its heat for a greater length of time than if otherwise disposed. I do not limit myself, however, to the exact 55 location of this mass of metallic substance. By providing the valve 15 in the steam-pipe 12 it is obvious that the volume of hydrogen generated may be accurately controlled—that is to say, by opening or closing the valve 60 15 to a greater or less extent, a greater or less quantity of high-pressure steam will be admitted to the stove and a greater or less volume of hydrogen gas will be generated.

65 It will be observed from the foregoing description that my invention can be applied to any old form of hot-blast stove and when so applied will operate in a satisfactory man-

ner for the production of a hydro-oxygen blast for supply to a furnace.

Having now described my invention, what 70 I claim as new, and desire to secure by Letters Patent, is—

1. In a hot-blast stove, a casing having brick checker-work therein, means for highly heating said checker-work, means for passing 75 steam therethrough and means therein for decomposing said steam.

2. In a hot-blast stove, a casing having brick checker-work therein, means for highly heating said checker-work, means for passing 80 steam therethrough and means therein for automatically decomposing said steam.

3. In a hot-blast stove, a casing having brick checker-work therein, means for highly heating said checker-work, means for passing 85 steam therethrough, means therein for decomposing said steam and means for regulating the supply of steam.

4. In a hot-blast stove, a casing having brick checker-work therein, means for highly heating said checker-work, means for passing 90 steam therethrough and a mass of refractory metallic substance therein for decomposing said steam.

5. In a hot-blast stove, a casing having brick 95 checker-work therein, means for highly heating said checker-work, means for passing steam therethrough, a mass of refractory metallic substance therein for decomposing said steam and means for regulating the supply 100 of steam.

6. In a hot-blast stove, a casing having brick checker-work therein, means for passing hot gases therethrough for heating said checker-work, means for cutting off the supply of hot 105 gases, means for passing steam therethrough and means therein for decomposing said steam.

7. In a hot-blast stove, a casing having brick checker-work therein, means for passing hot 110 gases therethrough for heating said checker-work, means for cutting off the supply of hot gases, means for passing steam therethrough and a mass of refractory metallic substance above 115 said checker-work for decomposing said steam.

8. A hot-blast stove, comprising a casing having a partition therein dividing the same into a combustion-chamber and regenerative chamber, which chambers communicate with each other at their upper ends, valved gas and air inlets leading into said combustion-chamber, and a hot-blast outlet leading therefrom, brick checker-work in said regenerative chamber terminating a short distance from the upper end thereof, a mass of refractory metallic substance located above said checker-work, a valved chimney-flue leading from the lower part of said regenerative chamber, a valved cold-air inlet leading into said regenerative chamber, and a steam-pipe communicating with the interior of said regenerative chamber below the mass of refractory metallic substance therein. 120 125 130

9. A hot-blast stove, comprising a casing having a partition therein dividing the same into a combustion-chamber and regenerative chamber, which chambers communicate with each other at their upper ends, valved gas and air inlets leading into said combustion-chamber, and a hot-blast outlet leading therefrom, brick checker-work in said regenerative chamber terminating a short distance from the upper end thereof, a mass of refractory metallic substance located above said checker-work, a valved chimney-flue leading from the lower part of said regenerative chamber, a valved cold-air inlet leading into said regenerative chamber, a steam-pipe leading into said regenerative chamber and discharging at a point below the mass of refractory substance therein, and a valve in said pipe for controlling the supply of steam. 25
10. A hot-blast stove, comprising a casing having a partition therein dividing the same into a combustion-chamber and regenerative chamber, which chambers communicate with each other at their upper ends, valved gas and air inlets leading into said combustion-chamber, and a hot-blast outlet leading therefrom, brick checker-work in said regenerative chamber terminating a short distance from the upper end thereof, a mass of refractory metallic substance located above said checker-work, a valved chimney-flue leading from the lower part of said regenerative chamber, a valved cold-air inlet leading into said regenerative chamber, and a steam-pipe having a vertical portion extending along the outside of said casing, and a horizontal portion extending through the side wall thereof, and provided with perforated branches located below the mass of refractory metallic substance in said regenerative chamber. 30
